UNITED STATES PATENT OFFICE.

CHARLES L. GEBAUER, OF CLEVELAND, OHIO.

METHOD OF PRODUCING FORMED METALLIC ARTICLES.

1,359,353.

Specification of Letters Patent. Patented Nov. 16, 1920.

No Drawing.

Application filed October 16, 1918. Serial No. 258,402.

To all whom it may concern:

Be it known that I, CHARLES L. GEBAUER, a citizen of the United States, residing at Cleveland, in the county of Cuyahoga and 5 State of Ohio, have invented a certain new and useful Improvement in Methods of Producing Formed Metallic Articles, of which the following is a full, clear, and exact description.

10 This invention relates to a method of forming metallic articles and has for its objects the provision of a new method whereby the production of certain classes of articles out of known, common, and fusible metals 15 can be facilitated, and whereby articles of use can be made out of metallic substances which hitherto could be worked by no known method.

The essence of my invention consists in 20 this that the metal in finely divided condition is compacted by great pressure into the substantial or exact size and shape of the article desired, after which it is brought to an elevated temperature less than its melting 25 point and maintained at that temperature for a considerable time. As a result of this treatment the particles cohere together in a solid, rigid, integral, homogeneous whole, which whole bears the finished shape and 30 size without necessity of machining or forming operations. Furthermore articles made in this way are generally more dense than if made by casting processes, while several metals can be treated thus which 35 from their infusibility can not be cast or from their hardness can not be machined after casting.

In my former Patent No. 1,223,322 granted April 17, 1917 and in my former applications Nos. 113,313 and 169,176, filed Aug. 5 1916, and May 17, 1917, respectively I have described articles made by compacting together two or more distinct metals of different fusing points and heating the same 45 to a temperature intermediate their several fusing points, which I formerly supposed was essential to success, but I have discovered that a solid rigid homogeneous article can be produced by compacting to the desired 50 shape either a finely divided single metal or finely divided mixture of metals and by suitably heat treating the same at a temperature less than that of fusion of the single metal in the first case or less than that 55 of any of the metals in the second case.

This invention is of use for a great many

purposes in the arts and sciences: for example in the construction of electrodes for vacuum tubes; in the production of all manner of tungsten or molybdenum articles for 60 electrical, chemical, mechanical or metallurgical uses; for the manufacture of dies, bearings, small parts, intricate patterns, etc., in iron, nickel, chromium, vanadium, titanium, or the alloys of same or like 65 metals; or in mixtures of titanium, vanadium, chromium, molybdenum, tungsten, manganese, iron, cobalt, nickel and the like as in making compound substances for special purposes to take the place of the expensive 70 casting, forging, and machining.

As one example of my improved process and of an article made therefrom I may make a valve part out of iron reduced by hydrogen, compressed hydraulically to the 75 shape desired under a pressure of, e. g., 2,000 pounds per square inch, and raised to a dull red heat (e. g., 800° C.) and maintained at that temperature for about one hour.

As another example I make puppet valves 80 for internal combustion engines by compacting iron, nickel, tungsten and chromium into a mold under a pressure of 4,000 pounds per square inch and afterward maintaining the same at a temperature of about 85 1200° C. for about half an hour.

As another example of my improved method I make tools and dies by compacting into a suitable mold a mixture of iron, molybdenum and chromium under a pressure of 90 1,000 pounds per square inch and thereafter heating the same for about one hour to a temperature of about 1200° C. In each of the above cases I preferably employ a preponderance of iron with about 10% of 95 chromium, the balance consisting of the remaining ingredients named.

If the mixture be first compacted under sufficient pressure I find that little or no change in shape or size will take place during the succeeding heat treatment. My invention is characterized by compacting together the pure metals in finely divided form to the ultimate shape required and subsequently treating them to a temperature 100 greater than their critical temperature but less than the melting point of any of them. By critical temperature I mean the lowest temperature at which molecular rearrangement of the material becomes possible. 105

This temperature varies very greatly for different substances, as is well known, where-

temperature of any component until the part 30
shall have cohered rigidly together, formed
by a plurality of points, lie above the same
temperature of tungsten, the desired form to a
metal article which of consists in mixing metals
together, whose melting point is above the same
critical great article, heating the lowest fusing
under finished intermedate critical maintaining shall have
all of points pressure, heating the highest, the
temperature and the components until together, producing alloys of iron
of the temperature rigidly containing-group metals, one or more
cohered rigidly together, of the temperature of tungsten
3. The articles consisting in mixing intimatly and one to a tempera- 45
metal and chromium metals, to the finished
group, iron group metals, to a tempera- 50
or more, chromium pressure the same and 1400° C.,
chromium under heating 1000° C. at this tempera-
ture desired, about the article coherent, 55
and maintaining thoroughly the same
and testimony whereof, I hereunto affix my
signature. In testimony whereof, I hereunto affix my
signature.

CHARLES L. GLAUER,
